Primary Examiner — Christy Nemeth

(57) **CLAIM**

The ornamental design for a charging dock as shown and described.

DESCRIPTION

FIG. 1 is a top perspective view of a charging dock showing our new design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is an enlarged view of a portion labeled as "9" on FIG. 2.

The dash-dash broken lines in the drawings illustrate portions of the charging dock that form no part of the claimed design. The dot-dash broken lines in the drawings illustrate the boundaries of the portions shown enlarged in the drawings and form no part of the claimed design.

1 Claim, 9 Drawing Sheets
